TOBACCO BOX WITH TIME CONTROLLED
LATCH

Robert F. Davis, Falls Church, Va.

Application January 7, 1948, Serial No. 1,035

7 Claims. (Cl. 70—269)

1

This invention relates to tobacco boxes intended for use by persons desiring to reduce the amount of tobacco which they consume and more particularly relates to a cigarette case having time-locking means arranged so that the case can be opened only at the expiration of predetermined time intervals to permit withdrawal or removal of cigarettes by the user.

The principal object of the invention is to provide for persons desirous of restricting themselves in their smoking habits, a novel tobacco box or cigarette case which is locked automatically upon closing for a predetermined time interval, after the expiration of which the box can be opened, if desired.

Another object of the invention is to provide a tobacco box having a time-latch in addition to the ordinary latch whereby access may be gained into the interior of the tobacco box only after the expiration of a predetermined time interval, if such access is desired.

Another object of the invention is the provision of a time-latch for tobacco boxes and timing means cooperating with the time-latch, which timing means may be adjusted so that the time-latch will remain in its locking position for predetermined time intervals which may be conveniently varied in accordance with the user's desires.

A further object of the invention is the provision of a tobacco box of the type having time-controlled latching means in addition to the ordinary latching means, which is simple in construction and which may be easily and economically manufactured.

A still further object of the invention is the provision of time-controlled latching means for boxes which is simple in construction and which may be easily and economically manufactured.

Other objects and advantages of this invention will be apparent upon consideration of the following detailed description of a preferred embodiment thereof in conjunction with the annexed drawings wherein:

Figure 1 is a plan view of a tobacco box embodying the principles of this invention and showing the closure member in its opened position;

Figure 2 is an enlarged sectional view taken along the line 2—2 of Figure 1;

Figure 3 is a sectional view similar to the sectional view of Figure 2 but showing the closure member in closed position and the time-latch in its locked position;

Figure 4 is a sectional view similar to Figure 5

2

3 but illustrating the time-latch in its unlocked position; and

Figure 5 is a fragmentary sectional view taken along the line 5—5 of Figure 3.

5 Referring in greater detail to the drawings, reference numeral 6 generally designates the body of the tobacco box having a bottom wall 7, side walls 8, a front wall 9 and a rear wall 10. Reference numeral 11 generally designates 10 the closure member of the box having a top wall 12, side walls 13, a front wall 14 and a rear wall 15. The rear walls 10 and 15, respectively, of the body 6 and the closure member 11 are hinged together at 16. The front, rear and side 15 walls of the body 6 are formed with flanges 17 and the front, rear and side walls of the closure member 11 are formed with flanges 18 which cooperate with flanges 17 to form a seal for the tobacco box when the box is in closed position. 20 The front wall 9 of the body 6 has a slot 19 formed therein and a flat spring 20 is slidably supported by brackets 21 which are rigidly attached to said front wall 9; also rigidly attached to the front wall 9 and the bottom wall 7 are 25 brackets 22 having apertures 23 formed therein; and rigidly attached to the front wall 9, rear wall 10 and bottom wall 7 are partitions 24. Rigidly attached to the front wall 14 of the closure member 11 is the L-shaped flange or keeper 25. Rigidly attached to the top wall 12 of the closure member 11 are the racks 26, having slots 27 formed therein.

30 Slidably mounted on the body 6 is a latch 28 having portion 29 thereof extending through 35 the slot 19 and a portion 30 thereof engaging said flat spring 20, in a manner such that the flat spring 20 urges the latch 28 toward the front wall 9 through which the portion 29 of the latch 28 extends. The latch 28 engages the flange 40 18 of the front wall 14 of the closure member 11 when the box is in closed position.

Time-latch 31 having apertures 32 and 33 formed therein is pivotally mounted on brackets 22 by means of a pin 34 extending through apertures 23 and 32. Generally designated by reference numeral 35 is the novel timing mechanism which comprises two hollow cylindrical members 36 and 37, the member 36 being slidable within, or telescopically arranged with respect to, the member 37.

The member 36 is closed at one end 38 and formed rigidly thereto are the brackets 39 having apertures 40 formed therein. The other end 41 of member 36 is internally threaded to receive 50 the threaded plug 42 having an aperture 43

formed therein. Housed within the member 36 is a fluid 44; a plunger 45 having an aperture 46 formed therein; a washer 47 carried by the plunger 45 and having a corresponding aperture 48 formed therein; a strong coil-spring 49; and a rod 50 having a head 51 formed on one end and having threads 52 on its other end. The rod 50 is adapted to extend through apertures 46, 48 and 43, apertures 46 and 48 being somewhat larger than the diameter of the rod and aperture 43 fitting the rod snugly, whereby the rod 50 carries the plunger 45 and the washer 47, and the aperture 43 serves as a guide for the rod 50 and as a liquid seal. One end of the strong coil-spring 49 bears against the washer 47 and the other end bears against the plug 42.

The member 37 is open at the end 53 to receive the end 41 of the member 36 and the other end of 37 is closed as at 54; said closed end 54 carries a bracket 55 having an aperture 56 formed therein; the end 54 is also threaded to receive the threads 52 of the rod 50. Housed within the member 37 is the weak coil-spring 58 arranged so that one of its ends engages the plug 42 and its other end engages the end 54 of 37.

In assembly, the timing mechanism 35 is pivotally attached at one end to the time-latch 31 by means of a pin 59 which extends through apertures 40 and 33. The other end of the timing mechanism 35 is selectively and pivotally supported in the slots 27 formed in the racks 26 by means of a pin 60 which extends through aperture 56 and is snugly received in a selected slot 27.

In operation, assuming that the tobacco box is in closed position, and that the timing period has expired so that the time-latch is in its disengaged position (Figure 4), the box may be opened upon depressing the portion 29 of the latch 28 against the action of the flat spring 20. When the box is opened (Figure 2), the strong coil-spring 49 is compressed; when the box is closed (Figure 3), the weak coil-spring 58 is compressed, and the strong coil-spring remains compressed by virtue of the force of the fluid 44 acting against the plunger 45. In this state the timing mechanism 35, acting in the manner of a dash pot, is operable upon the time-latch 31 maintaining engagement of the time-latch with the L shaped flange or keeper 25, and the box cannot be opened until sufficient fluid 44 bleeds past the plunger 45. As the fluid bleeds past the plunger the plunger is moved to the left of the position thereof illustrated in Figure 3 until the head 51 of the rod 50 is engaged thereby. When fluid 44 has seeped past the plunger 45, the force of the strong coil-spring 49 is effective against the action of the weak coil-spring 58, in moving the time-latch 31 in a clockwise direction about its pivot, thus disengaging the time-latch from the L shaped flange or keeper (illustrated in Figure 4), and the box may be opened. It is significant to note, however, that the box need not be opened at this time as the latch 28 will maintain the box in closed position until the user wishes to open it.

The timing interval during which the timing mechanism is acting to maintain the box in a locked state, may be varied by a simple adjustment of the timing mechanism to the desired slots 27 formed in the racks 26. If the timing mechanism is supported by the slots near the end *a* of the racks 26, the time locking interval will be of minimum duration; if the timing mechanism is supported by the slots near the end *b* of the

racks 26, the time locking interval will be of maximum duration.

It is to be understood that the form of my invention herewith shown and described, is a preferred example of the same and that various changes in the shape, size, and arrangement of parts may be resorted to without departing from the spirit of my invention or the scope of the sub-joined claims; also it is understood that the novel time-lock disclosed herein can be used for containers other than a tobacco box.

What is claimed is:

1. In a tobacco box having a body member and a closure member hinged thereto, the improvement which comprises latching means mounted on said tobacco box and timing means controlling said latching means, said timing means including a hollow member; said hollow member being closed and operable on said latch at one end and having an aperture formed at its opposite end, said hollow member housing a fluid, a rod having a stop formed thereon, a floating plunger mounted on said rod for longitudinal movement with respect thereto and a resilient member acting on the plunger limiting its longitudinal movement between said stop and said resilient member, said rod being arranged to extend through said aperture; a member cooperating with said hollow member, said member adapted to be supported selectively by said box, having means operable on said rod and including resilient means operable on said hollow member, said resilient member acting on said plunger being stronger than said resilient means operable on said hollow member whereby, upon closing the tobacco box a dash pot effect is attained through the medium of said fluid acting in opposition to the longitudinal movement of said floating plunger, which effect maintains said latching means in locked position for a predetermined interval of time.

2. In a tobacco box having a body member and a closure member hinged thereto, the improvement which comprises latching means, said timing means mounted on the tobacco box and timing means controlling said latching means, said timing means including two hollow members telescoped one within the other; one of said hollow members being closed and operable on said latch at one end and having an aperture formed at its opposite end; said one of said hollow members housing a fluid, a strong compression spring, a rod having a stop formed thereon and a floating plunger mounted on said rod for longitudinal movement with respect thereto, said rod extending through said aperture and the longitudinal movement of said plunger being limited by said stop in one direction and said spring in the other direction; the other of said members adapted to be supported selectively by said box, having means operable on said rod and housing a weak compression spring which bears upon said one of said hollow members; whereby upon closing the tobacco box said fluid opposes the longitudinal movement of said floating plunger in the manner of a dash pot and said latching means is locked for a predetermined time interval.

3. In a tobacco box having a body member and a closure member hinged thereto, the improvement which includes latching means pivotally mounted on the tobacco box and timing means controlling said latching means, said timing means including two hollow members telescoped one within the other; one of said hollow

members being closed and pivotally attached to said latch at one end, having an aperture formed at its opposite end and containing a fluid, a strong coil-spring, a rod having a stop formed thereon and a member mounted on said rod for longitudinal movement with respect thereto, said rod extending through said aperture and the longitudinal movement of said member being limited by said stop and strong coil-spring; the other of said hollow members arranged to be supported selectively by said box, having means to rigidly attach said rod thereto and housing a weak coil-spring arranged to act upon said one of said hollow members; whereby, when the box is opened, the plunger engages the stop formed on the rod and compresses the strong coil-spring, and when the box is closed, the weak coil-spring is compressed and the strong coil-spring is maintained in its compressed state by virtue of fluid pressure acting against the plunger and the resultant force of the time-locking means acts against the time-latch until the fluid bleeds past said plunger allowing said plunger to resume its normal position at the end of the rod, whereupon the force of the strong coil-spring acting in the same direction disengages the time-latch.

4. In a tobacco box having a top and a bottom section each including four flanged side walls, said sections being hinged together along one side, the improvement which comprises a latch slidably mounted on one of said side walls of one of said sections having a portion thereof extending without the box and a portion thereof adapted to engage one of said flanged side walls of the other of said sections; spring means mounted on said one of said side walls cooperating with said latch and urging the latch toward said one of said side walls; a plurality of racks mounted on said other of said sections, said racks having slots formed therein; a time-latch pivotally mounted on a bracket rigidly attached to said one of said sections, said time-latch adapted to cooperate with a keeper mounted on a side wall of said other of said sections; timing means controlling the time-latch, said timing means including two hollow elongated members telescoped one within the other; one of said elongated members being closed and pivotally attached to said time-latch at one end, having an aperture formed at its opposite end and housing a strong coil-spring, a rod having a stop formed on one end thereof, and a floating plunger mounted on the rod for longitudinal movement with respect thereto, the longitudinal movement of the plunger being limited by said stop and coil-spring and said rod arranged to extend through said aperture; the other of the elongated members being adapted to be selectively supported in said slots formed in said racks and having means to rigidly attach said rod thereto and housing a weak coil-spring, arranged to act upon said one of the elongated members; whereby, when the box is opened, the plunger engages the stop formed on the rod and compresses the strong coil-spring, and when the box is closed, the weak coil-spring is compressed and the strong coil-spring is maintained in its compressed state by virtue of fluid pressure acting against the plunger and the resultant force of the time-locking means acts against the time-latch until the fluid bleeds past said plunger allowing said plunger to resume its normal position at the end of the rod, whereupon the force of the strong coil-spring acting in the same direction disengages the time-latch.

5. In a box including a body member and a closure member hinged thereto, the improvement comprising latching means mounted on one of said members and timing means controlling said latching means; said timing means including a hollow item closed at one end and having means engaging said latching means, first resilient means biasing said hollow item in such a direction as to exert a force on said latching means 10 in latching direction, the opposite end of said hollow item having an aperture formed therein, a rod connected to the other of said members and extending into said hollow item through said aperture, stop means on said rod within said hollow item, a piston having a slow leakage aperture slidably carried by said rod between between said stop means and the apertured end of said hollow item, second resilient means biasing said piston toward said stop means and exerting a force on 15 said hollow item in opposition to said first resilient means, said second resilient means, after a predetermined time controlled by leakage of air through said slow leakage aperture, causing said piston to engage said stop means and thereafter exerting a force on said hollow item sufficient to 20 overcome the force of said first resilient means and to release said latching means.

6. In a box including a body member and a closure member hinged thereto, the improvement 30 that comprises latching means mounted on one of said members and timing means interconnecting said latching means and said other member for controlling said latching means; said timing means including an elongated hollow item closed 35 on one end and having an aperture formed in the other end, a rod extending into said hollow item through said aperture, said rod and said hollow item being arranged for relative longitudinal movement, stop means on said rod within said hollow item, a piston housed in said hollow item between said stop means and the apertured end of said hollow item and slidably carried on said rod, said closed end of said hollow item and said piston defining therebetween a chamber having 40 leakage means, a first resilient means longitudinally biasing said hollow item in one direction and said rod in an opposite direction, a second resilient means biasing said piston toward said stop means and exerting a force on said hollow 45 item in opposition to said first resilient means, said second resilient means, after a predetermined time controlled by leakage of air through said leakage means, causing said piston to engage said stop means and thereafter overcoming said 50 first resilient means and longitudinally biasing said hollow item and said rod in directions opposite to the direction exerted by said first resilient means.

7. A timing device that comprises an elongated 60 hollow item closed on one end and having an aperture formed in the other end, a rod extending into said hollow item through said aperture, said rod and said hollow item being arranged for relative longitudinal movement, stop means on said rod within said hollow item, a piston housed in said hollow items between said stop means and the apertured end of said hollow item and slidably carried on said rod, said closed end of said hollow item and said piston defining therebetween a chamber having leakage means, a first resilient means longitudinally biasing said hollow item in one direction and said rod in an opposite direction, a second resilient means biasing said piston toward said stop means and exerting 65 a force on said hollow item in opposition to said 75

first resilient means, said second resilient means, after a predetermined time controlled by leakage of fluid through said leakage means, causing said piston to engage said stop means and thereafter overcoming said first resilient means and longitudinally biasing said hollow item and said rod in directions opposite to the direction exerted by said first resilient means.
